HARRY LYON, OF BROCKTON, MASSACHUSETTS, ASSIGNOR TO JOHN A. BARBOUR AND PERLEY E. BARBOUR, BOTH OF BROCKTON, MASSACHUSETTS, DOING BUSINESS AS COPARTNERS UNDER THE NAME OF BROCKTON RAND COMPANY.

METHOD OF CUTTING SHEETS OR SHOULDERS OF SOLE-LEATHER INTO STRIPS FOR WELTING.

1,179,119.

Specification of Letters Patent. Patented Apr. 11, 1916.

Application filed October 13, 1915. Serial No. 55,637.

To all whom it may concern:

Be it known that I, HARRY LYON, a citizen of the United States, residing at Brockton, in the county of Plymouth and State of Massachusetts, have invented new and useful Improvements in Methods of Cutting Sheets or Shoulders of Sole-Leather into Strips for Welting, of which the following is a specification.

10 This invention relates to the manufacture of welting for boots and shoes, from the irregularly shaped sheets of sole leather usually called shoulders.

A shoulder of tanned sole leather has one 15 relatively long edge presenting an irregular reentrant curve. It has been customary heretofore to subdivide a shoulder into strips or blanks, each wide enough for several welts, by curved cuts, the first cut following as closely as possible the reentrant curvature of the longer edge, and the succeeding cuts being as nearly parallel with the first cut as is possible, each blank being subsequently subdivided into welt strips of 25 operative width. This method of subdividing welt strips involves a considerable waste of leather, and other objections, as more fully described hereinafter.

My invention has for its object to obviate 30 the objections to the said prior method, and it consists in the improvements which I will now proceed to describe and claim.

In the accompanying drawings forming a part of this specification, the figure represents 35 a side view of a sheet or shoulder of sole leather, and illustrates my improved method of subdividing the same.

In the drawings, *a* represents a sheet or shoulder of tanned sole leather having a 40 relatively long longitudinal edge *b* presenting an irregular reentrant curve.

Heretofore it has been the common practice to subdivide the shoulder into blanks by first making a curved cut following the 45 edge as closely as possible, and then making a series of curved cuts substantially parallel with the first cut, each cut extending through the entire length and thickness of the leather. These cuts have been necessarily made by a hand-operated knife making the cut progressively. The depth of the curve of the edge *b* varies to such an extent in different shoulders that it is impossible

to form a curved cut which is exactly parallel with and at an exactly predetermined 55 distance from the next cut. For this reason, it is not possible to subdivide a shoulder by curved cuts, into strips each of the width required for an operative welt, without more or less waste of material in the 60 shape of narrow waste strips or trimmings at one edge of the strip, and it has therefore been necessary heretofore to make each strip or blank of a width sufficient for several welts, usually four or more, and to subsequently subdivide the blank into welt 65 strips, the operation being attended with more or less waste of material.

It is important that the ends of a welt strip be accurately formed at right angles 70 with its longitudinal edges in order that when a number of strips are spliced or joined end to end to form an elongated welt strip of indeterminate length, the edges of the elongated strip will be continuous, without projections or slight angles at the joints. It is difficult when the shoulder is subdivided by curved cuts, to avoid such shoulders or slight angles.

The relatively wide strips or blanks as 75 heretofore formed involve waste of leather in cutting, in trimming the ends of the blanks, and in cutting away imperfect portions such as are due to slaughter cuts in the leather. Further waste of leather is due to 80 the fact that the blanks have to be cut wider than the aggregate width of the welt strips into which they are subdivided, so that in forming the welt strips narrow waste strips or "strings" are produced. Moreover, the 85 shrinkage of a relatively wide strip or blank is often such that the predetermined number of full width welt strips cannot be produced from a blank, at least one of the welt strips having to be of reduced width.

To overcome the objections above recited, I cut a shoulder as indicated in the drawing, my preferred mode of procedure being as follows: I first remove the marginal portion having the edge *b* by a straight cut 10 10, 100 thus forming a straight base edge on the strip, said edge being approximately parallel with a portion of the edge *b*. After removing the marginal portion 11 separated from the shoulder by the cut 10 10, I proceed to subdivide the body of the shoulder 105

by a series of straight cuts 12 12 into relatively narrow straight edged strips 13, each of which may be of the width required for an operative welt strip, although I prefer to make each strip 13 of a width which is a multiple of the width of a single welt strip and subsequently subdivide it into a plurality of welt strips of operative width and without waste of material by a straight cut 5 or cuts 14 14, as indicated by dotted lines. Each straight cut 10—10 may be conveniently formed by an elongated knife forming the entire cut at one operation, and each cut forms a base edge which is a factor in 15 the determination of the direction of the cut next formed, said edge being adapted to cooperate with suitable gaging means, so that the successive base edges may be accurately formed, each at an exactly predetermined 20 distance from the next. The removed portion 11 may be similarly subdivided, as indicated. The straight edged welt strips thus produced are adapted to be joined together or spliced without forming projections, 25 shoulders or slight angles at the joints. All waste in the form of edge trimmings or strings is eliminated as above described. The waste of material involved by the improved method of cutting is further reduced, as will be apparent from a comparison 30 of the shaded portions in Fig. 2 with those in Fig. 1, the reduction of waste being noticeable not only at the marginal portions of the shoulder but also in the vicinity of a 35 slaughter cut *f*, back wrinkles *g*, or other imperfections in the body of the shoulder.

When the strips 13 are of only double the width of a single welt strip, the shrinkage

of the strips 13 does not noticeably affect the width of the ultimate welt strips. 40

Having described my invention, I claim:

1. The improvement in the method of cutting into welting a shoulder of sole leather presenting an irregular reentrant curve at one edge, which consists in severing said shoulder on a straight line approximately parallel with the major portion of said curve, and completing the cutting by severing portions on opposite sides of the initial cut into a series of welt strips. 45 50

2. An improvement in the method of cutting into welting a shoulder of sole leather presenting an irregular reentrant curve at one edge, which consists in severing said shoulder on a straight line adjacent the major portion of the reentrant curve, and completing the cutting by severing portions on opposite sides of the initial cut into a series of welt strips. 55 60

3. An improvement in the method of cutting into welting a shoulder of sole leather presenting an irregular reentrant curve at one edge, which consists in severing said shoulder on a straight line approximately parallel with the major portion of said curve, and completing the cutting by severing portions on opposite sides of the initial cut into a series of welt strips, said cuts being spaced to form relatively wide strips 65 70 the width of which is a multiple of the width of an operative welt strip, and then subdividing said wide strips into operative welt strips.

In testimony whereof I have affixed my signature.

HARRY LYON.
